AUTOMATICALLY EXTENSIBLE HOISTING MAST

Filed June 7, 1922

FIG. 1.

FIG. 3.

FIG. 2.

INVENTOR

P. H. Mallinckrodt.

UNITED STATES PATENT OFFICE.

PHILIP H. MALLINCKRODT, OF SALT LAKE CITY, UTAH.

AUTOMATICALLY-EXTENSIBLE HOISTING MAST.

Application filed June 7, 1922. Serial No. 566,604.

To all whom it may concern:

Be it known that I, PHILIP H. MALLINCKRODT, a citizen of the United States, and a resident of Salt Lake City, county of Salt Lake, and State of Utah, have invented a certain new and useful Automatically-Extensible Hoisting Mast, of which the following, together with the accompanying drawing, forms a full, clear, and exact specification, such as will enable others skilled in the art to which it appertains to make and use the same.

My invention relates to an automatically extensible hoisting mast, and its principal objects are:

First. To provide a device whereby a load may be hoisted to a certain desired height, in cases where only a part of that height is available for placing a permanent, rigid, hoisting structure.

Second. To provide means whereby a load suspended from a rope or other wrapping connector, may be hoisted to a pre-determined height by pulling on the said rope from a certain rigid structure which is less in height than the pre-determined height.

Third. To make it possible to hoist a load from a point below a given point, to a third point above the given point, by simply winding up a rope or other wrapping connector having one end thereof attached to the said load, and the other end attached to a hoisting mechanism located below the given point.

Fourth. To provide a device whereby a load may be moved from one point, to a second point remote from the first point, by the progressive shortening of a continuous rope or other wrapping connector passing over a fulcrum member located between the two said points, the device being so arranged that when the load has reached a pre-determined point of its travel, a rigid member shall be automatically engaged to furnish a support for the load while the load is being carried to the said second point.

Fifth. To provide a device which shall be simple and durable.

Sixth. To supply an efficient mechanism for the purpose mentioned.

In attaining the objects outlined above, I provide a mast portion which is fixed, relatively to a second or movable mast portion.

The movable portion may be connected to

the fixed portion in any suitable manner, so that there will be a telescoping action between the two. As the top of the movable portion may be mounted one or more rotatable members, such as grooved sheaves or chain wheels, and near the bottom of the movable member I mount another rotatable member. At the top of the stationary structure I also mount a rotatable member; a wrapping connector, such as a chain or wire rope, is provided for hoisting, and this connector is adapted to be connected to the load in any suitable manner, for instance by a hook, clevis, or other equivalent device. From the load, the rope extends upwardly, over the rotatable member of the movable mast portion, down to the sheave fixed at the lower part of the movable mast portion up again around the sheave at the top of the fixed mast portion, and then down to any suitable hoisting device, such as a chain block or winch.

In winding up the rope, the load will begin to rise and will be lifted to the top of the movable mast portion, on which is fixed a stop member located at a point somewhat below the sheave; a second stop portion, which may be fixed to the rope at a point somewhat above the load, and adapted to contact the first stop member. Upon the further winding up of the rope it begins lifting the movable member, the load of course continuing to move up accompanied by the movable member. The lifting of the load continues to the limit of motion possible between the two mast portions.

This device is designed especially for lifting loads out of basements opening on to side walks where the openings must normally be kept covered and where permanent hoisting structures would not be allowable on account of obstructing the sidewalks. Other instances of usefulness will readily occur to the skilled mechanic.

The present device further might include a plurality of mast sections extensibly disposed in relation to each other, and adapted to automatically have the extension travel take place after a stop portion located on a rope or chain, which is suitably interconnected with the mast portions, has come into contact with a second stop portion located on one of the said mast sections.

The features of this invention on which

the protection of Letters Patent is desired, are collectively grouped in the claims concluding this specification.

In the drawing which illustrates merely 5 one embodiment of this invention as applied to a so-called "sidewalk hoist,"

Fig. 1 is a plan view;

Fig. 2, a side elevation showing the traveling parts in the lowered position;

10 Fig. 3, a view similar to Fig. 2, a portion being broken away, and showing the traveling parts in an elevated position.

Throughout the different views, similar parts are designated by similar reference 15 numerals.

Referring to the drawing, 20 represents a fixed mast portion which may consist of two steel channels spaced apart from each other, as shown in Fig. 1. This mast may 20 be anchored to the floor 21 in any well-known manner, and the top of the mast may be anchored to the wall 24 by means of a yoke brace 25.

25 A movable mast portion 26, which may be made of metallic pipe, may be placed to one side of the fixed mast 20 and be adapted to travel along the latter in fixed lateral relation thereto, by means of the brackets 27 and 28, each of which may embrace the movable mast portion, and extend in two branches overlapping the sides of the mast 20. The bracket 27 may carry two traction wheels 30, which may be journaled on the pins 31, these wheels being disposed on each 30 side of the mast 20 in a manner to engage the channel members of the mast, between the flanges thereof. A slight amount of clearance is left between the circumferences of the wheels and the inside surfaces of the 35 flanges so that the wheels will turn freely on the pins 31, and so they may contact either one of the flange surfaces, though in this instance, the disposal of the load will pull the wheel 30 towards the flange nearest 40 the movable member 26. Another traction wheel 32 may be rotatably mounted on the pin 34 between the side portions of the bracket 28. The bracket 28 may have lip 45 portions 35 forming guards on each side of the mast and extending inwardly over the flanges thereof to prevent any disengagement between the bracket 28 and the mast 20. The traction wheel 32 may bear against the flat faces of the mast channels as a track.

50 At the top of the movable portion 26 there may be an overhanging arm formed of two steel channels 36, which may be attached thereto by pins or bolts 37. The two channels 36 may be connected by a plate 60 portion 38, which may form the integral front part of a knee brace 39, which in turn may have a foot portion 40 rigidly fastened to the mast 26. Between the arm channels 36 may be mounted the chain 65 sheaves 41 and 42 which are rotatable on

the pins 43 and 44 respectively, the pins being secured in the channels 36. Another chain sheave 45 may be rotatably disposed in the bracket 27 and still another sheave 46 may be rotatably mounted between the 70 channels of the mast 20.

A bracket 47 may be rigidly mounted on the mast 20 and a chain block 48, having the usual hook 49, may be suspended from the end of the bracket 47. The chain block 75 need not be particularly described here, further than to state that it may be of the spur-gear type with an internal braking mechanism for supporting a load at any stage of the hoisting. Such chain blocks are made by various manufacturers and the general construction and use thereof are well known.

The operating wheel of the chain block is shown at 50, and the operating chain at 51. A hook for supporting a load, is shown at 52, and a load chain at 53, extending from the hook 52 upwardly to and around the chain wheel 41, and then, in order, to and around the chain wheels 42, 45 and 46. Inasmuch as the chain blocks named, usually pull the load chain from the bottom, an idler chain wheel 54 is provided, around which the load chain 53 passes as it comes from the chain wheel 46. From the idler 90 54, the load chain 53 passes up into and through the chain block.

In hoisting the load, the operator pulls the hand chain 51 in the proper direction, thereby starting the hook 52 upwardly, and continuing until the upper part 56 of the hook 52, which forms a stop portion, strikes the plate 36 which forms a second stop portion adapted to co-act with the first stop portion 56. A further pull on the load chain 53 will leave that part of the load chain between the chain sheaves 41 and 45, stationary relatively to the mast portion 26, and will cause the movable portion 26 to move upwardly to any desired height 100 within the capacity of the structure, for instance, to the position shown in Fig. 3.

In cases where it is desired to bring the load over to either side of the hatchway 57, as indicated by the arrows in Fig. 1, this may be accomplished by mounting the mast 20 in such a way (not shown) that it may have an angular movement around its vertical axis, instead of mounting it rigidly as is shown in the present drawing. This, however, can be accomplished by any skilled mechanic and so forms no part of my invention.

110 It will be noticed that the brackets 27 and 28 with their appurtenances, may be said to form a carriage for mounting the mast 26, and the bottom 60 of the mast 26, may form a stop for limiting the downward travel of the mast.

115 While a desirable embodiment of this in-

vention is described herein, it is to be clearly understood that the details of the invention may, or may not, be shown in the preferred forms; further, that the preferred forms 5 may be considerably varied from time to time, depending upon the circumstances and conditions governing, and governed by, the development of this invention and the arts to which it is incident, so that the scope 10 of this invention is to be interpreted from the claims in which its spirit is broadly generalized.

Having fully described my invention, what I claim is:

15 1. In a device of the kind described, a mast portion adapted to movably engage a second mast portion and to be longitudinally guided therewith, a sheave on the said first mast portion, a second sheave on the said 20 first mast portion at a point below the first sheave, another sheave mounted on the said second mast portion at a point above the said second sheave of the first mast portion, a wrapping connector having one end depending from the first sheave, while the other end extends to, and around, the second sheave of the first mast portion and around the other sheave of the second mast portion in the order named; a 25 hoisting mechanism to which the other end of the wrapping connector may be attached, a stop portion located on the said wrapping connector at a point below the said first sheave, and a stop portion located on the 30 said first mast portion at a point between the said first sheave and the said first stop portion.

2. The combination with two mast portions relatively movable to each other longitudinally of a stop portion located on one 35 of the said mast portions, a hoisting

mechanism mounted on the other mast portion, a wrapping connector having a free end with a stop portion fixed thereto in operable relation to the first stop portion, 45 the said hoisting mechanism adapted to engage the other end of the said wrapping connector, and a plurality of guide members disposed on both the said mast portions in such a manner that the said wrapping connector may pass around the said guide members, and the hoisting mechanism, and by winding up the said wrapping connector, shall first cause a travel of the wrapping connector alone, until the said stop portions 50 come in contact, and then shall cause a certain travel between the said mast portions. 55

3. A mast, a mast extension arranged for longitudinal movement along the said mast, a guide sheave on the mast, an upper guide sheave and a lower guide sheave on the mast extension, a wrapping connector arranged to pass simultaneously over the said guide sheaves, and a stop on the said wrapping connector, said stop being arranged to engage the said mast extension at a point of its travel. 60

4. In combination, a structure, an extension arranged to rise above the said structure, a wrapping connector passing operatively from the said structure to the said extension, a guide for said connector on said structure, guides for said connector spaced apart from each other on said extension, a stop at one end of the said connector arranged to engage the extension, and means for drawing the said connector over the guide on said structure. 65 70 75

In testimony whereof, I sign my name hereto.

PHILIP H. MALLINCKRODT.
